JACOB BEESLEY AND JOSIAH J. FERRIS, OF PHILADELPHIA, PENNSYLVANIA, ASSIGNORS TO CHARLES NOBLE & CO., OF SAME PLACE.

Design No. 4,916, dated May 23, 1871.

DESIGN FOR THE PLATES OF A STOVE.

The Schedule referred to in these Letters Patent and making part of the same.

We, JACOB BEESLEY and JOSIAH J. FERRIS, of the city of Philadelphia, in the State of Pennsylvania, have invented and produced a new and original ornamental Design for the plates of a Stove, of which the following is a specification.

Our design relates to those cylindrical sheet-iron stoves having cast-iron caps, bases, and intervening illuminating-chambers; and

The nature of our design for the same is fully represented in the accompanying photographic illustrations, to which reference is made—

a b c d being the profile or upright contour of the base, and *e* the bass-relief ornamental figures thereon.

f g h, the profile or upright contour of the cap, and *i* the bass-relief ornamental figures thereon.

k l M N o, the profile or upright contour of the illuminating-chamber, and *p q* the bass-relief ornamental figures thereon.

r s t, the contour and ornamentalations of the legs of the base, and *u v* the contour of, and *w* the bass-relief ornamental figures, and monogram (C. N. & Co.) on

the hood *X* for covering hot-air draught-holes in the sheet-iron sides of a stove.

Claims.

We claim as our invention—

1. The design for the bass-relief figures *i* on the said cap of a stove, as shown.
2. The design for the profile or contour *k l M N o* of the illuminating-chamber of a stove, as shown.
3. The design for the bass-relief figures *p p' p'' q* on the illuminating-chamber, as shown.
4. The design for the contour and ornamentalations *r s t* of the legs of a stove, as shown.
5. The design for the contour *u v*, and the ornamental figures and monogram *w*, on the covering-hood *X* of a stove, as shown.
